UNITED STATES PATENT OFFICE.

HERBERT D. BLAKEMORE, OF MOLINE, ILLINOIS.

DISK HARROW.

SPECIFICATION forming part of Letters Patent No. 410,573, dated September 10, 1889.

Application filed October 27, 1888. Serial No. 289,308. (No model.)

To all whom it may concern:

Be it known that I, HERBERT D. BLAKEMORE, of the city of Moline, in the county of Rock Island and State of Illinois, have invented certain new and useful Improvements 5 in Disk Harrows, of which the following is a specification.

My invention relates to that class of earth-cultivating machines known as "disk harrows" 10 or "cultivators," wherein the stirring or pulverizing of the soil is effected by means of metal disks rotating in a vertical plane, and especially to that style of machine wherein the angle of the disks with reference to the line 15 of draft may be varied or changed as the varying condition of the soil or the character of the work to be done may require.

This invention consists of a series of independently-pivoted disks connected to move 20 simultaneously in the same direction, each disk having the pivot vertically over and in the plane of its cutting-edge, so that the adjustment of the disks is effected without displacing them laterally, and thereby lessening 25 the strain on the parts during the adjustment.

The invention also consists in certain constructions and arrangements of parts, herein-after described.

30 In the drawings, Figure 1 is a plan view of a machine embodying my invention, in which two series of disks are employed, each series of disks being capable of independent adjustment with relation to the line of draft. Fig. 35 2 is a longitudinal section taken to one side of the draft-beam. Fig. 3 is a cross-section illustrating one of the disks and means employed for attaching it to the beam. Fig. 4 is a plan view showing a modified form of my 40 invention and in which two series of disks are employed, both series of disks being adapted to be simultaneously adjusted in the same direction. Fig. 5 is a detail front elevation of the machine shown in Fig. 4. Figs. 45 6 and 7 are plan views of the central portions of another modified form, and showing the method of simultaneously adjusting several series of disks in opposite directions. Fig. 8 is a detail view of a yoke-thimble forming a 50 bearing for the disk yoke or hanger.

The principle of my invention may be em-

bodied in a machine carrying any ordinary number of disks arranged either in series or in a single set, and will be effective whether a flat-sided, curved, or any other shaped disk 55 be employed.

For convenience I have illustrated and will describe my invention as embodied in a harrow carrying twelve concavo-convex disks arranged in two series of six each, the disks of 60 each series arranged in relatively opposite directions with the concavity of the disks of each series facing toward the center of the machine. I also employ a single stationary beam at right angles to the draft-pole, this 65 being the simplest as well as most desirable form of machine.

A is the harrow-beam, which is arranged at right angles to the draft pole or beam B and to which it is firmly secured. The draft pole 70 or beam B extends in rear of the harrow-beam A, and at or near its rear extremity there is secured by a curved spring a a driver's seat b, while in front of the harrow-beam are provided the usual draft attachment. (Not 75 shown.) The harrow-beam and draft-pole are braced and rigidly held together by the braces c, arranged to connect said pole-beam either in front or in rear of the latter, or both, as may be desired or found necessary. 80

C represents a disk yoke or hanger, which comprises two downwardly-projecting hangers d, between which is journaled a disk D. The hangers d are connected at their upper ends and provided with a centrally-located 85 and preferably integral stem or spindle d', which extends through an opening d² in the draft-beam A, and is adapted to turn laterally therein.

E represents thimbles which fit in the opening, both at the upper and lower end thereof. These thimbles each comprise a cylindrical hollow portion e, having one or more tapering or wedge-shaped ribs e' on their exterior faces, and are provided at one end with a 90 wide annular flange e². These thimbles are driven into the opening d² until the inner faces of the annular flanges are flush with the surface of the beam, the ribs e' entering the wood on the sides of the hole and serving to 95 securely hold the thimbles in place without the use of screw-bolts or other extraneous

means. The hollow cylindrical portions of the thimbles form a bearing for the yoke stem or spindle d' , and the annular flange of the lower thimble affords a seat for the arch or connecting portion between the two hangers. The flange of the upper thimble affords a bearing for a yoke-arm, as will be hereinafter more fully described. Upon the rear of the disk-yoke, extending downwardly from its arch, is a thin sheet of metal f , either cast integral therewith or secured thereto, and provided with a slit conforming to the shape of the disk, which serves not only as a scraper therefor, but also strengthens the yoke. That portion of the spindle which projects through and beyond the opening d^2 in the beam A is provided with a square or angular upper end or head f' , which fits in a correspondingly-shaped opening in a yoke-arm f^2 , and the latter is held in place upon said head by means of a nut f^3 , which engages the threaded upper end of said spindle. The outer or front ends of the yoke-arms (of which there is one for each yoke) are pivotally connected to lever-rods F, which are in turn pivoted at their inner ends to an actuating lever or levers G, pivoted to the beam A, or other suitable part of the machine.

The lever or levers G are provided with spring-actuated pawls g , adapted to be operated by finger-levers g' , suitably pivoted and connected with said pawls. The pawls are adapted to engage segment-racks H, which are preferably secured to the beam A, and the operating-levers G are in easy reach of the driver's seat. It will thus be seen that the disk-yokes and their disks are by means of the yoke-arms, the connecting-rods, and levers brought within control of the driver, while the machine is in operation, and that by the employment of the pawls and segment-racks that the disks may be readily locked in their adjusted position. The disk is, as shown, pivoted between the hangers d , and is provided with a long hollow extension or hub on its concave side to retain the disk in a vertical position with its cutting-edge in the same plane as the yoke stem or pivot and prevent its wabbling. Where each of the series of disks is to be independently adjustable, each series of yoke-arms is provided with its separate connecting-rod, which is attached to an independent lever working in an independent segment-rack, as shown in Figs. 1 and 2. Where all the disks are to be actuated at one time in the same direction, all the yoke-arms are pivotally connected to a single rod which extends nearly the entire length of the beam A, and a single lever and rack are employed, as shown in Fig. 4. In this case the connecting-rod is provided with an upwardly-extending pin h ,

which works in an elongated slot in the outer end of the lever.

In Figs. 6 and 7 I have illustrated another form of means for actuating the disks. In this case a single lever I is employed, and this lever is provided with curved arms i , having curved slots i' , which are engaged by pins or extensions i^2 on the inner ends of the connecting-rods. By this construction it will be seen that upon operating the lever the disks will be simultaneously adjusted in opposite directions.

In the several forms of machine shown when the lever-handles are in line with the draft the disks are in like line. When the lever-handles are adjusted out of line with the draft, the disks, through the connecting-rods, yoke-arms, and spindle, are thrown out of line with the draft, and by means of the segment-rack and spring are secured or locked in any desired adjustment.

It will be observed that by the relative construction and arrangement of the parts, as herein shown and described, the disks are capable of adjustment or angling in and out from the center of the machine, as shown by dotted lines in Figs. 1, 6, and 7; an obvious advantage over many of the prior inventions in which the adjustment is only in one direction—that is, either in or out.

Obviously my invention may, with a few changes rendered necessary by the difference in general construction, be embodied in harrows having a rectangular, triangular, or other shaped frame, or in a harrow constructed with a series of parallel beams secured, as in the present case, at right angles to the pole, and I do not, therefore, limit myself to the particular form of machine here shown; nor do I limit myself to the specific construction of the parts described, as changes which fall within the scope of my invention may from time to time suggest themselves.

Having thus fully described my invention, what I claim as new, and desire to secure by Letters Patent, is—

The combination, with the harrow-beam, the disks, and their yokes having spindles free to turn in said beam, of the yoke-arms fast at one end to the said spindles, the lever-rods pivotally connecting the outer ends of the yoke-arms, and the lever G, pivotally connected to the beam on a common vertical pivot, with their shorter arms crossed and pivotally connected to the adjacent ends of the lever, substantially as shown and described.

HERBERT D. BLAKEMORE.
